LITHOGRAPHIC ETCHING SOLUTION

Everett F. Carman, Rutherford, N. J., assignor to
 Interchemical Corporation, New York, N. Y., a
 corporation of Ohio

No Drawing. Application March 6, 1940,
 Serial No. 322,573

2 Claims. (Cl. 41—42)

This invention relates to etching solutions for lithographing plates, and is particularly directed to etching solutions which attack chromium but not copper or conventional exposed bichromated coatings used to prepare lithographic plates.

There has recently been developed a new printing plate, comprising a grained coppered printing surface covered with a thin coating of water-receptive chromium in the non-printing areas. In the preparation of such plates, a grained copper plate is coated with chromium, and a bichromated solution of gelatin, gum arabic or polyvinyl alcohol is coated over the chromium. The sensitized coating is then exposed to light through a suitable positive, and the undeveloped coating removed, leaving the chromium bare in the printing portions. The chromium may be etched by any chemical solution which dissolves chromium but which does not attack the copper. However, the ordinary aqueous solutions of chemicals tend to attack the developed coating as well, particularly in halftone structures, where the coating may exist only as an isolated dot. As a result, the ordinary aqueous chemical solutions can be used only to produce line prints, and are not satisfactory for half tones.

I have discovered etching solutions which make possible the etching of chromium while avoiding any attack on copper, or on exposed bichromated gelatin, gum arabic or polyvinyl alcohol. These solutions comprise mixtures of aqueous hydrochloric acid with completely water miscible glycol containing more carbon atoms than hydroxyl groups, using between about 3 to

6 parts of glycol by volume to 1 part of concentrated aqueous acid (37%). The typical glycols of this type include diethylene glycol, propylene glycol, and dipropylene glycol.

Typical examples of my invention are the following:

Example 1

Mix 3 volumes of propylene glycol with 10
 1 volume of 37% hydrochloric acid

Example 2

Mix 6 volumes of diethylene glycol with 15
 1 volume of 37% hydrochloric acid

Example 3

Mix 3 volumes of dipropylene glycol with 20
 1 volume of 37% hydrochloric acid

Variations may be made in the examples, without departing from the scope of the invention, which is described in the claims.

I claim:

1. An etching solution for lithographic plates comprising one volume of aqueous hydrochloric acid, and from 3 to 6 volumes of a water-miscible glycol containing more carbon atoms than hydroxyl groups.

2. An etching solution for lithographing plates consisting of about 1 volume of 37% aqueous hydrochloric acid and 3 volumes of propylene glycol.

EVERETT F. CARMAN.
